ABSTRACT: In a printer, character-bearing type elements moving along a print line selectively impact a ribbon against a document backed by a platen to print on the document. The platen is automatically retracted at the end of each print cycle to provide adequate clearance for advancing the document for the next line of printing, whereupon it is advanced so as to provide an optimum space relation with the type elements for printing the next line.

FIG. 12

INCREMENTING PLATEN

CROSS-REFERENCE TO RELATED APPLICATIONS

This invention is related to and is used with the inventions of copending application Ser. No. 661,929, now U.S. Pat. No. 3,499,516, of Frederick W. Schaaf; and Ser. No. 661,989, now U.S. Pat. No. 3,452,335, of James M. Cunningham both filed Aug. 21, 1967, and is shown applied to a system utilizing the basic control circuits and structures thereof.

FIELD OF THE INVENTION

This invention relates to high-speed printers, and in particular to an automatic platen structure and control system therefor.

DESCRIPTION OF PRIOR ART

Heretofore, platens in printers have either been manually adjusted to accommodate different thicknesses of forms or have even been automatically adjusted for different forms thicknesses, only at the time the type carrier gate is closed on the form to commence a printing operation and the adjustment thus achieved remains constant for the printing of the entire document.

SUMMARY OF THE INVENTION

Generally stated, it is an object of this invention to provide an improved printer.

More specifically, it is an object of this invention to provide for controlling the relative spacing of a character bearing type element and an impact member on opposite sides of a document so as to provide a predetermined optimum spacing therebetween during printing and a greater spacing during advance of the document on which a printing operation is being performed.

Another object of the invention is to provide for automatically increasing the spacing between type bearing elements and an impact member such as a platen used therewith for impacting a document to print thereon in timed relation with the printing of each line of the document.

An important object of the invention is to provide for resiliently biasing a print platen in one direction and actuating it in the opposite direction and releasably maintaining it against said biasing.

Yet another important object of this invention is to provide for automatically latching a print platen in a printing position against the bias of spring retracting means by releasable latch means and for releasing the latch means at the end of each print line.

Another important object of the invention is to insure that a movable print platen is initially positioned in a printing position and is retracted to provide more clearance for the document before advancing the document.

Still another important object of the invention is to retract a print platen before the carriage moves and to restore it to the print position when the carriage stops.

The foregoing and other objects, features and advantages of the invention will be apparent from the following more particular description of a preferred embodiment of the invention as illustrated in the accompanying drawing.

DESCRIPTION OF THE DRAWING

In the drawing:

FIG. 1 is a partial schematic showing of one type of printer apparatus with which the invention may be used;

FIGS. 2a through 2t taken together provide a schematic circuit diagram of a tapeless carriage control system which may be used with the carriage of FIG. 1 and the invention in one of its forms;

FIG. 2u is a schematic block circuit diagram of the system of FIGS. 2a-2t showing the relation therewith of the invention;

FIG. 3 is a block diagram showing the arrangement of FIGS. 2a through 2t;

FIG. 4 is a chart showing typical carriage control codes;

FIG. 5 is a chart showing typical codes to define line positions other than the last line of a form;

FIGS. 6a through 6b are charts showing valid commands for control of a printer carriage utilizing the circuits of FIGS. 2a-2t;

FIG. 7 is a clock timing chart for the system of FIGS. 2a-2t;

FIG. 8 is a plan view of a platen structure utilizing the present invention;

FIG. 9 is a front elevational view of the platen structure of FIG. 8;

FIG. 10 is an enlarged partly sectioned end elevational view of the platen structure of FIGS. 8 and 9 with the cartridge of FIG. 1 shown in part;

FIG. 11 is a schematic circuit diagram of the platen controls of FIG. 1 embodying the invention; and

FIG. 12 shows timing curves illustrating the timing relations for various signals in FIG. 11.

DESCRIPTION OF A PREFERRED EMBODIMENT

FIG. 1 shows a printer apparatus of one type with which the present invention may be used, and comprises a type cartridge

25 10 having a plurality of individual type carrier elements 11 movable in a continuous path on a stationary frame 12. A portion of the path of motion of the type elements 11 includes a straight portion along which printing can occur and which hereinafter is referred to as the print line. Each type element

30 11 has one or more different engraved characters on the surface thereof adjacent the print line. Plural sequences of type characters are obtained by assembling the type elements 11 in predetermined arrangements on the frame 12. The type elements 11 are driven preferably in the form of a train along the frame 12 so that they travel at a constant velocity and are maintained in abutting relation along the straight portion of the path of travel.

The printer apparatus of FIG. 1 is a front printer, but is generally similar to the back printer which is described in U.S.

40 Pat. No. 3,241,480, which issued on Mar. 22, 1966 to James M. Cunningham, and in accordance with well-known operational principles thereof a paper document or form 13 is positioned behind an ink ribbon 14 or the like which in turn is positioned immediately adjacent the type elements 11 over

45 the print line portion thereof. The ribbon 14 may be fed in a suitable manner between spools 15 (only one of which is shown) along the line of travel of the type elements. The paper document 13, however, is fed transversely to the direction of motion of the type. Guide bars 17 and 18 and carriage forms

50 feed tractors 19 coact to support and move the paper document 13 in the proper line of travel. Generally, printing occurs while the paper document 13 is stationary relative to the print line. On completion of a print cycle, the paper document 13 is advanced one or more spaces by the carriage tractors 19 to a position where a new line of data may be printed. The means for feeding the paper document 13 in synchronism with operation of the print mechanism are well known in the art and may

55 include a carriage drive motor 22 comprising, for example, dual motor units 22-1 and 22-2 or the like connected to shafts 20 by means of pulleys 21 or the like of the carriage tractors 19.

In the printer apparatus of FIG. 1, the arrangement shown is for a front printer. Details of the type element used in the front printer are shown in FIG. 10 wherein a type carrier element 11 is shown having one or more pivotally mounted fingers 11a, each with a type character 11b on the depending free end of a finger 11a. The type carrier elements 11 are, as described in the Cunningham patent, slidably mounted on a guide rail. As

70 shown, printing occurs when the type characters 11b on the type elements 11 impact against the ribbon 14, paper document 13 and a platen 23 having associated platen controls 25. The impacting occurs at various print positions along the print line to eventually form a complete line of data. For this purpose, a plurality of print hammers 24 are mounted beneath the

75

cartridge 10 and in front of the depending type character bearing fingers 11a of the type carrier elements 11, which are guided by a guide rail 12a on the frame 12. The type carrier elements 11 are retained on the guide rail by a cover plate 12b or the like, as shown in FIGS. 1 and 10, in front of the print medium 13. Print hammers 24 are arranged to be uniformly spaced so that one print hammer 24 occupies each print position along the print line, and the hammers 24 are aligned in a single row parallel to the print line. Each print hammer 24 is a part of an individual hammer unit which comprises an electromagnet 26 with an armature 28 and a pushrod connector element 30 with bias springs 32 which maintain the hammers 24 out of contact with the type fingers 11a when the electromagnet 26 is deenergized. Each hammer 24 is individually operable and the operation of the various hammers 24 occurs selectively at random positions along the print line in accordance with instructions from suitable control means (not shown) which comprise a type tracking device and a coacting storage device which indicates the particular data to be printed. Further details of a suitable control system may be more fully understood by reference to U.S. Pat. No. 2,993,437 of F. M. Demer and E. J. Grenchus for a "High-Speed Printer," which issued July 25, 1961.

As shown in FIGS. 1 and 10, printing is designed to occur when a print hammer 24 impacts a type character bearing finger 11a against the ribbon 14 and document 13 which is backed up by a bar or platen 23. In accordance with the present invention, to provide a minimum of clearance to minimize the necessary type finger movement when printing, and yet provide adequate clearance for advancing the document 13 past the type fingers between printing operations, the platen 23 is made movable. As shown in FIGS. 8-10, the platen 23 comprises generally an elongated flat bar having a smooth edge surface 23a and diagonal slots 27 which receive guide blocks 29 having U-shaped cap plates 29a secured by means of screws 29b for maintaining the platen in place, (the plate 29a is omitted from the right-hand block in FIGS. 8 and 9 to show other details more clearly) and secured to an adjustable support 31 which is used to set the initial clearance of the platen when a hinged carrier gate (not shown) on which the cartridge 10 is mounted (as shown in the Cunningham application Ser. No. 661,989). For the purposes of the present invention, the support 31 may be considered fixed, since it does remain fixed during the entire printing operation, at least until the form is changed. The blocks 29 are provided with springs 33 projecting from the rear sides which bias the platen 23 to the rearmost or retracted position.

The platen controls 25 as shown in FIG. 8 comprise an electromagnet operator 34 having an operating winding 35 which when energized, urges a movable armature extension 35a of an armature 35b to overcome the bias of springs 33 and drive the platen 23 to the left and forward. An electromagnetic latch 36 is provided having a pivotal latch armature 36a actuated by a latch winding 36b to seat on a detent shoulder 23b of the platen 23 when the platen is advanced and retain it in the advanced position. A retract winding 36c operates the armature 36a to unseat the latch armature 36a, release the platen 23 and permit the springs 33 to retract it to the rearmost position.

Referring to FIG. 11, it will be seen that in the platen controls 25 the platen forward or electromagnet operating winding 35 is energized through pick and hold drivers 210 and 212. They are energized through a single shot 214 which energizes the pick driver 210 directly and turns on a solenoid latch 216 to energize the hold driver 212. The single shot 214 is energized through OR 218, either from AND 220 by a print gate latch signal from print gate latch 254 and the ON output of a timeout latch 222, or by a not low-speed signal through single shot 226. The timeout latch 222 is set by a not carriage settling signal through a holdover time delay 224 and is reset by a print trigger signal from a print trigger 250. The single shot 214 also energizes the latch magnet winding 36b by energizing a pick driver 244 through inverter 240 and single shot 242, and turning on a magnet latch 236 to energize a hold driver 238.

The retract winding 36c is energized through pick and hold drivers 228 and 230 by a low-speed signal through OR 234' and single shot 232, and by the low-speed signal which energizes driver 230 directly, respectively. The timeout latch 222 is also used to energize the pick driver 228 through OR 234'. The output of single shot 232 is connected to reset latch 236 through OR 235 when the retract magnet winding 36c is energized. AND 246 which is gated by the ON output of the timeout latch 222 and the output of single shot 214 provides for print inhibit.

Referring to FIG. 11, it will be seen that the print trigger signal is provided by the print trigger 250 which is turned on through AND 252 by a print gate latch 254, not carriage settling and the platen print inhibit signal from AND 246. The print gate latch 254 is turned on by a print write gate trigger 256, which is gated ON through AND D256a and OFF through AND 256b, through AND 258 in response to service-out delay 1 signal and a write command from a control unit through AND 260. OR 259 provides for reset of latch 254. Inverter 261, AND 262, single shot 263 and inverter 264 provide print trigger signals to OR 259 and AND 252. FIG. 12 shows timing curves which illustrate the operation of the platen controls 25 in response to low-speed and low-speed signals.

Control of the tractor drive motor for advancing the paper document 13 to the different line positions at which printing is desired is controlled by means such as described in the copending Schaa application, which utilizes a carriage control buffer 40 wherein are stored binary coded representations of the channels containing the different skip commands, these representations being stored at the respective line positions to which a skip operation is to be effected.

The carriage control buffer 40 is a 16×16 core array containing 256 bytes, with core planes for an end of document flag bit 1, 2, 4, and 8 bits and a parity bit. As shown in FIGS. 2g and 2h, the buffer 40 is provided with a plurality of X-drivers 42 and corresponding X-switches 44 for providing drive current in the X-direction. Y-drivers 46 and Y-switches 48 provide the corresponding Y-drive. Inhibit drivers 50 are provided for selectively controlling the writing of information into the buffer 40 in response to data on the carriage control buffer data bus 52. Sense amplifiers 54 and AND's 55 provide for readout of the buffer 40, flag, 1, 2, 4, 8 and P-bit lines of the several core planes.

Addressing of the buffer 40 is effected by means of a CCB address register 56 shown in FIGS. 2d and 2e, and which comprises a plurality of triggers 56-1, 56-2, 56-4 through 56-128 arranged in a binary addressing fashion for addressing of the buffer 40. Triggers 56-1 and 56-2 are decoded by AND's 43a-43d (FIG. 2g) to form unique output lines for controlling the X-drivers 42, while triggers 56-4 and 56-8 are similarly decoded by AND's 45a-45d to control the X-switches 44. Likewise, triggers 56-16 and 56-32 address the Y-drivers 46 through AND's 43e-43h while triggers 56-64 and 56-128 address the Y-switches 48 through AND's 45e-45h. The address register 56 is advanced by pulses from a clock 60 shown in FIGS. 2i and 2j, and which comprises a plurality of triggers 60-1 through 6-4 and decode AND's 61a-61k with associated inverters 63a-d, single shots 63e-f and drivers 63g-i. Drive of the clock triggers 60-1 through 60-4 is obtained from a clock run trigger 62 through AND 64 in conjunction with pulses from oscillator 36. The trigger 62 is set through AND 68 and OR 70 by an adapter start signal from OR 84 (FIG. 2n) during loading of the buffer 40 and by a carriage clock start signal from AND 180 (FIG. 2f) during readout of the buffer 40.

In order to avoid inadvertent modification of the carriage control buffer contents, loading of the buffer 40 is effected in response to a CCB load command which follows a specific channel tag line sequence which is sensed and stored in a gate load latch 72a shown in FIG. 2b and which must be set before the CCB load latch 72c can be set. A UCB load latch 72b also shown, controls loading of a universal character buffer (not shown). These latches 75a-c respond to commands on the

bus out lines 69 through decode AND's 74a—74c, respectively. AND 59 and OR 47 provide an invalid CCB address 1 signal at AND 59 (FIG. 2p). Required NOT signals are obtained from the bus out lines 69 through inverters 71a—k (FIG. 2a) and decode AND's 73a—f (FIG. 2a). OR 71m provides a bus out 6 or 7 signal. Control of the CCB address register 56 (FIGS. 2d—e) during loading is effected by a buffer control latch 80, shown in FIG. 2f, which is set by the CCB load signal through OR 81 or by the output of AND 79. Data from the channel is loaded under the control of the I/O tag lines service-in and service-out which gate signals from OR 38c and one of OR's 39a—c through AND 82 and OR 84 (FIG. 2n) which provides an adapter clock start signal for setting the clock trigger 62 (FIG. 2i). OR 39d provides an input to OR 84, while OR 39a also provides inputs to OR's 38a—c. Data is gated to a CCB register 83 (FIG. 2k) comprising a plurality of latches 83a—f for comparison through OR's 76a—h (FIG. 2l) and AND's 77a—c with command signals in a command register 78, comprising latches 78a—e which are controlled from the bus out 69 through OR's 85a—f and decode AND's 86a—k from the system bus out 69 with the following byte relations.

Bus bit:

	CCB Register bit
4	8
5	4
6	2
7	1
3	F

The data is gated to the register 83 (FIG. 2k) by means of a plurality of AND's 87a through 87l and OR's 88a—f to the latches 83a—f and to the carriage control buffer data bus 52 for controlling the inhibit drivers 50 (FIG. 2g) for storing data bits in the several planes of the different positions in the buffer 40 of FIG. 2h. AND's 87m and 87n provide gating signals to different ones of the AND's 87a—l for manual and normal operations, respectively. Exclusive OR's 89a—e (FIG. 2k) provide a parity bit for the latch 83a. Reset of latches 83a—f is provided through AND 90.

Readout of the carriage control buffer 40 (FIGS. 2g—h) in connection with carriage operations may occur with or without printing. Operation of the carriage tractors 19 is effected by energizing the motor windings 22a—d and 22A—D (FIG. 2t) of a dual carriage motor 22—1, 22—2 of FIG. 1, and which may comprise stepper motors of a well-known type, through a plurality of AND's 94A, 94A, 94B and 94B in response to energization of carriage drive pulse circuit 96 comprising stepping triggers 96A and 96B as shown in FIG. 2s and as described in more detail in the copending application Ser. No. 661,930 (Docket EN967049) of Roger C. Hull and Eugene T. Kozol filed Aug. 21, 1967. These triggers 96A and 96B are sequentially stepped in response to a stepper motor advance signal from AND 98 through OR 100, in response to an initial advance signal from a single shot 102, or pulses from a plurality of emitter pickup heads 103, 104, and 106 associated with a slotted emitter disc 111 driven by motor 22—1, 22—2 through amplifiers 108a—c, single shots 109a—b and AND's 110a—g (FIG. 2r). The outputs from the emitter heads 103—104—06 are gated by means of output signals from AND's 112 and 114 from a low-speed latch 120, a high-speed latch 122, and/or an ultra high-speed latch 124 (FIG. 2t). Selective control of these high and ultra high-speed latches 122 and 124 is effected through AND's 121a—d, OR's 123k—q, and AND's 123a—j, inverter 125 and single shot 128 in conjunction with OR's 126a and 126b and a shift latch 126 which is set by the OFF outputs of the high and ultra high-speed latches 122 and 124 through OR 126a and single shots 127a and 127b, respectively, and inhibits the low- and high-speed latch outputs momentarily when downshifting to a lower speed, by a carriage counter 130 (FIG. 2r) comprising a plurality of triggers 130a—c advanced in a binary fashion by feedback pulses from the AND 98, and which through a decode circuit of AND's 132a—c provides decode 4, decode 5, and decode 7 output signals, respectively. The ultra high-speed emitter signal is produced from the high-speed emitter

head 106 by inverting it through inverter 105 to drive single shot 107. Stop pulses are provided through AND's 110a—c by stop circuits 133, 134, and 135, each of which comprises, as shown for circuit 133, a plurality of cascade arranged single shot 133a, b, c, and d with associated inverters 133e and f and OR 133g to provide a series of three stop pulses. OR 191 (FIG. 2t) and AND's 94A, 94A, 94B and 94B (FIG. 2s) serve to inhibit drive to the motor 22—2 when the pedestal drive signal from OR 191 is removed by the low-speed latch 120 being turned off.

DESCRIPTION OF OPERATION

Operation of the clock 60 during readout operations is effected under the control of a carriage control buffer address counter gate trigger 136 (FIG. 2f) which is set by the decode 4 signal from the decode circuit AND 132a (FIG. 2r). Operation of the carriage drive circuit 96 (FIG. 2s) is effected by means of a carriage start latch 140 (FIG. 2f) which is turned on either by an immediate carriage go signal from single shot 138 and AND 139 (FIG. 2q) or by a carriage go after print signal from AND 148 (FIG. 2f) if a print operation is involved. These signals set the latch 140 through OR 144 and AND 142 or AND 146, respectively. Set of the start latch 140 provides a carriage go pulse through AND 141 for setting the low-speed latch 120 (FIG. 2t) to start carriage operation. Stopping of the carriage is effected by resetting the low-speed latch 120 through operation of a line counter 150 (FIGS. 2d—e) which comprises a plurality of triggers 150—1, 150—2, 150—4 and 150—8 arranged in a binary stepping fashion. AND's 151 and 152 provide line counter 15 and line counter 1 signals, respectively. Inverter 153 is used to inhibit further advance of the counter when a count of 15 is reached without a compare, through AND 154a.

The low-speed latch 120 (FIG. 2t) is reset by a carriage register reset signal generated at single shot 161 through OR 160 (FIG. 2f), in response to the output of a stop AND 162 which responds to the decode 5 and line counter 15 signals with a carriage not skip signal from OR 163.

Status latches 164a—d (FIG. 2p) provide busy, channel end, and device end gate and device end signals, indicative of the operating condition of the apparatus, through decode AND's 165a—g, associated OR's 166a—g and AND's 92 and 185. Sense latches 176a—e (FIG. 2q) provide indications of the equipment error conditions.

Tag line signals represented by the service-in and status-in signals are produced by tag line latches 168a, 168b (FIG. 2o) for control purposes, through decode AND's 169a—g and OR's 170a—d. Bus assembly circuits are provided in FIGS. 2m—n, including decode AND's 157a—f, AND's 158a—q, OR's 167a—f and line drivers 155a—i for assembling the bus in bits. A parity bit for the bus in is provided by exclusive OR's 178a—g, inverter 179 and AND 181. Bus out parity check 55 is provided by exclusive OR's 189a—h through line receivers 156a—i.

In operation, the carriage control buffer 40 (FIG. 2h) is loaded in response to a CCB load command through decode AND 74c from over the bus out lines 69 which sets the CCB load latch 72c, provided that the CCB gate load latch 72a has been previously set by a command through decode AND 74a (FIG. 2b). The CCB load latch 72c initializes the operation by resetting the CCB address register 56 (FIGS. 2d—e) to address 1 through OR's 171, 172, single shot 173, and OR 174 and sets the buffer control latch 80 through OR 81 (FIG. 2f). The buffer control signal gates the triggers 56—1 and 56—2 of the CCB address register 56 (FIGS. 2d—e) at each RO time to permit sequencing of the carriage control buffer addresses in each clock cycle.

Since the command to load the buffer 40 has been stored in latch 72c, and the buffer address has been modified to the correct starting point, buffer byte 1, the control unit is prepared to receive data from the channel. The data is loaded under control of the I/O tag lines service-in and service-out through AND 82 (FIG. 2n), which produces the adapter clock start signal at OR 84. This sets the clock run trigger 62 (FIG. 2i)

through OR 70 and AND 68, starting the clock 60 and permitting it to take one cycle. The clock run trigger 62 resets at the fall of trigger 60-4 of the clock 60, which corresponds to RO time as shown in FIG. 7. Since the clock cycle is 2 microseconds, which is less than the minimum data period for a byte of data received from the bus out lines 69, the clock 60 will return to RO before the next data byte is available.

A CCB parity bit is generated from the CCB register contents and is inserted in the bit latch 83a of the register 83 on an odd parity basis through the exclusive OR's 89a-d of parity circuit 89 (FIGS. 2k-l). The read drivers and switches are turned on for R1, R2, and R3 time as shown by the timing chart in FIG. 7. However, the contents of bit 1 in the carriage control buffer 40 are not recycled because a strobe signal (which is a delayed signal produced by a time generator 38 in response to a read signal, rises only on a read operation and is used to gate the output of the sense amplifiers 54 in AND's 55, did not rise. Accordingly, the outputs of the sense amplifiers 54 are not gated in AND's 55, and the old contents of the carriage control buffer 40 are erased during loading.

As described previously, data is loaded starting from position 1, and reset of the CCB address register 56 occurs with the coincidence of RO and the CCB flag bit indicating the end of the line to be printed from AND 175 through OR 174 (FIGS. 2d-e). The clock 60 continues through the end of the current cycle and at RO the carriage control buffer 40 address will be advanced to position 2. The contents of position 1 remain in the CCB register 83 (FIG. 2k). Should a program error occur during loading, as evidenced by the 0, 1, or 2 bits on bus out, a program error is indicated by invalid CCB load signal generated by latch 176b through OR 173a, AND 177c or AND 177b and OR 173b (FIG. 2q). Other sense latches 176a, 176c, 176d and 176e function with AND 177a and OR 173c to provide a command reject signal; OR 173a to provide an invalid flag signal; and OR 173e to provide a CCB parity check and a carriage failure check. AND 177d provides another input to latch 176b through OR 173a, and 177c and OR 173b.

Carriage operations may occur with or without printing. The carriage commands shown in FIGS. 7a and 6b reflect this by describing the byte structure for an operation with a print command or for a carriage command alone. If the function is to space/skip immediate, the carriage control latch 75a (FIG. 2c) is set through AND 63b, OR 65b and decode AND 66a. AND's 66c and 66d provide inputs to latches 75c and 75d, respectively. If a write and space/skip command is sensed, the write latch 75b will be set through OR 51a and OR 51b, AND 63a, OR 65a, and decode AND 66b. In either case, a carriage function is indicated so that gate carriage register signal rises at OR 77 (FIG. 2c) to permit loading of the bus out bits from bus out 69 to the carriage command register 78 (FIG. 21) through AND's 86a, c-e-g and i.

To perform a carriage function, the carriage start latch 140 (FIG. 2f) is set through OR 144 either by the carriage go after print signal from AND 146, and AND 148, or the immediate carriage go signal from AND 142 through single shot 138 and AND 139 (FIG. 2q) when a carriage command bit configuration exists from bus out and the command out tag line rises. If the carriage is not already in motion, carriage start latch 140 starts it by bringing up carriage GO at AND 141 (FIG. 2f). The carriage will be started in the low-speed mode by the carriage go signal setting the low-speed latch 120 (FIG. 2t).

Assuming a carriage command is entered into the command register 78 (FIG. 21) gated by a gate command register signal from AND 65B (one of a group of AND's 65A-65C providing signal inputs to different ones of the command latches 75a-75d) to space one line, then the skip latch 78e of the carriage command register 78 will be off, so that the 4 and 8 triggers 150-4 and 150-8 of the line counter 150 (FIGS. 2d-e) will be set (FIG. 2d) by the not skip signal from AND 149. The not 2 bit of the single space command sets the 2 trigger 150-2 of the line counter 150 through AND 147. Accordingly, line triggers 150-2, 150-4, and 150-8 will be set and a single space

condition has been decoded from the carriage command register 78 (FIG. 2l). The line counter 150 registers a count of 14 so the single space latch 91 (FIG. 2l) is set through decode AND 145a and OR 143. AND 145b provides for operating latch 91 when a command to skip one space is received. Carriage motion starts as follows: The carriage go signal from AND 141 (FIG. 2f) sets the low-speed latch 120 (FIG. 2t) giving the carriage an initial advance pulse from single shot 102 (FIG. 2s) and starting motion by advancing the motor drive triggers 96A and 96B, which switch current in the motor drive windings 22a-d and 22A-D in a well-known manner. Additional advance pulses occur from the motor emitters 103 or 104 through AND 98 and OR 100 from AND 110d or 110e, so that the carriage counter 130 is advanced by the stepper motor advance signal and its contents are decoded by the decode circuits 132 (FIG. 2r). For a pitch of six lines per inch, eight pulses total are required for a single space advance, and for eight lines per inch, six pulses are required. At decode 4 time the CCB address counter gate trigger 136 (FIG. 2f) is set, causing set of the buffer control latch 80 through AND 79 and OR 81, and starting the clock 60 by raising carriage clock start at AND 180 and applying a signal to clock run trigger 62 through OR 70 and AND 68 (FIG. 2i). Reset of CCB address counter gate trigger 136 is effected at W1 time, being gated in AND 136a by the buffer control signal and the CCB address counter gate trigger 136 ON output. AND 136b provides proper timing relative to settling of the carriage tractors 19. The fall of CCB address counter gate trigger 136 causes the OFF output to gate reset of buffer control latch 80 at RO in AND 196. The clock 60 takes one cycle stopping in RO. In doing so, the contents of the carriage control buffer 40 byte 2 are read out to the CCB register 83 (FIG. 2k) and the CCB address register 56 (FIGS. 2d-160e) advances to position 3 at RO time. The line counter carriage register reset was advanced to count 15 at the fall of R1 time. Line counter 15 and W2 reset the carriage start latch carriage command through OR 131, AND 85 and OR 115.

When the carriage counter 130 (FIG. 2r) advances to decode 5, a stop pulse is generated at OR 160 through AND 162 (FIG. 2f). AND's 160a and 160b provide other inputs to OR 160. This turns on the carriage-register-reset signal at single shot 161 which resets the line counter 150, through OR 182 (FIG. 2d) and the carriage-command register 78 through OR 8tf (FIG. 21). It also turns on the device-end-gate latch 164c through OR 183 (FIG. 2p) causing the device-end latch 164d to turn on through AND 185 and OR 186, producing the device-end signal in the channel-status byte. This indicates to the channel that the carriage operation is ended.

The line counter reset signal from the line counter 150 (FIGS. 2d-e) also initiates the actual carriage stopping sequence by resetting the low-speed latch 120 (FIG. 2t), which starts a single shot string of three stop pulses through AND 110b, stop circuit 134 (assuming eight-lines-per-inch pitch), OR 100, and AND 98, and gates out or inhibits the feedback pulses from the motor emitters 103-4-6 (FIG. 2r).

The carriage counter 130 advances six pulses per line when printing at eight lines per inch, and eight pulses per line when printing at six lines per inch. The particular pitch is determined by a line pitch latch 188 through switch 190 and AND's 191a-ba-c are gated to bring up the decode 4 signal four pulses from the end of the line space, decode 5 signal three pulses from the end of a line space and the decode 7 signal one pulse from the end of a line space. The carriage counter 130 is reset on the eighth or last pulse by decode 8 signal from single shots 195 and 193.

For a double or triple space, the same carriage start, line counter control and CCB address register timing applies for the first line space. But for additional line spaces, the clock 60 is started by each decode 4 signal which sets the CCB address counter gate trigger 136 (FIG. 2f) starting the clock 60 (FIG. 2i) for one cycle. Each clock cycle advances the line counter 150 (FIGS. 2d-e). When the line counter 150 contents is 15, line counter 15 signal rises at AND 151 (FIG. 2e) and brings

up the stop pulse at AND 162 (FIG. 2f) at decode 5 time, starting the stop sequence which stops the carriage mechanism. Carriage register reset signal from the single shot 161 starts the carriage operation ending sequence as previously described. Note that the line counter 150 is initialized to a count of 13 through AND's 116 and 149 for a double space, and to a count of 12 through AND 149 alone for a triple space at the start of the space command.

Description of a low-speed skip operation is as follows: A skip immediate or skip after write command will be entered in the carriage command register 78 (FIG. 2l) and the bus out bit 0 will turn on the skip latch 78e in the register 78. The carriage start latch 140 (FIG. 2f) will be turned on by immediate carriage go or carriage go after print from AND 142 or AND 146 through OR 144. The CCB address counter gate trigger 136 is set by the carriage start signal through AND 192 and OR 194 and brings up the carriage clock start signal. The buffer control latch 80 will be set by the ON output of the CCB address counter gate trigger 136 gating the advance of the CCB address register 56 at RO time (FIGS. 2d-e). The clock 60 will advance the CCB address register 56 and the line counter 150. The carriage mechanism has been activated by the carriage go signal generated by the carriage start latch 140 and AND 141 (FIG. 2f).

The carriage start latch 140 is not reset, so the return of the clock 60 to RO again sets the CCB address counter gate trigger 136 through AND 192 and OR 194 (FIG. 2f) permitting the clock 60 to run an additional cycle. The line counter 150 and the CCB address register 56 advance, and the contents of the addressed bit location in the carriage control buffer 40 is read out to the carriage register 83 each clock cycle.

Assume that the skip channel digit stored in bits 1, 2, 4, and 8 of the carriage command register 78 (FIG. 2l) is stored in byte 5 of the carriage control buffer 40, and assume also that the forms 13 were located at line 1 when the carriage skip was started. As shown in the timing diagram of FIG. 7, a carriage register compare signal will occur at AND 77c (FIG. 2l) when the contents of carriage control buffer 40 position 5 is read into the CCB register 83 (FIG. 2k). This will set the carriage compare latch 159 through AND 113 and OR 117 (FIG. 2f). Further advance of the CCB address register 56 is inhibited after RO of the current clock cycle because CCB address counter gate trigger 136 is reset through AND 67 and OR 85. The CCB address register 56 will have advanced four times. Carriage compare signal from the latch 159 resets CCB address counter gate trigger 136 and the carriage start latch 140. The line counter 150 (FIGS. 2d-e) is complemented by the carriage compare signal over conductor 195 (gated by an input on line 197 through OR 154c from AND 154b, one of the two inputs from AND's 154a-154b) (FIG. 2d) so that its contents are changed from a count of 4 to a count of 11. The clock 60 completes the present cycle and stops in RO. The carriage go signal from the carriage start latch 140 (FIG. 2f) started the carriage by setting the low-speed latch 120 (FIG. 2t).

Only 8 microseconds will have elapsed, so the first decode 4 signal from the carriage counter 130 (FIG. 2r) will not have yet been generated. The first decode 4 signal sets the CCB address counter gate trigger 136 (FIG. 2f) causing the clock 60 (FIG. 2i) to take one cycle. The three following carriage emitter signals from AND 98 (FIG. 2s) do likewise. The line counter 150 content is now 15, bringing up line counter 15 signal at AND 151, which brings up the stop pulse at AND 162. Carriage register reset signal from OR 160 and single shot 161 (FIG. 2f) resets the command register 78 (FIG. 2l) and the line counter 150 (FIGS. 2d-e), and initiates the carriage stopping sequence by resetting the low-speed latch 120. Reset of the low-speed latch 120 (FIG. 2t) causes the mechanism to stop as previously described. The carriage has advanced four lines from 1 to 5. The carriage control buffer 40 has advanced from position 2 to position 6.

Assume that the command is loaded to skip to a forms channel 15 lines spaces or more from the present print line. Specifically assume that the channel digit is stored in position 20 of the carriage control buffer 40 (FIGS. 2g-h) and line 1 was the last line printed. In this case, a carriage compare signal from carriage compare latch 159 (FIG. 2f) will not occur during 15 initial advances of the line counter 150. When the line counter 150 reaches a count of 15, inverter 153 inhibits further advance of the line counter 150. In each of the 15 clock pulses the CCB address register 56 (FIGS. 2d-e) was advanced, so that the carriage control buffer 40 address is 16 line spaces ahead of the actual forms line. The first and successive decode 4 pulses from the decode circuit 132a (FIG. 2r) will force additional stepping of the CCB address register 56 (FIGS. 2d-e) until carriage register compare signal occurs at AND 77c, at carriage control buffer 40 address 20, turning on carriage compare latch 159 at W0 time through AND 113 and OR 117 (FIG. 2f). Further advance of the CCB address register 150 is inhibited when buffer control latch 80 is gated down after reset of CCB address counter gate trigger 136 at W1 time after compare by RO through AND 196. Since the buffer control signal is a d-c level signal applied to one of the d-c gates of CCB 1 trigger 56-1 (FIG. 2d), RO will also advance the CCB address register 56 to 21 even though RO resets buffer control latch 80 (FIG. 2f). The line counter 150 (FIGS. 2d-e) is complemented to zero by the carriage compare signal, and carriage advance continues. Each decode 4 signal causes the advance of the line counter 150 as previously described, since line counter 15 signal came down when the line counter 150 was complemented. Fifteen line spaces after carriage compare signal occurred, line counter 15 signal rises at AND 151 (FIG. 2e) generating the stop pulse at AND 162 (FIG. 2f). The same stopping procedure will occur as described previously and the form 13 will stop in position 20 with the CCB address register 56 containing address 21.

When the line counter 150 (FIGS. 2d-e) initially advances to 15 without a compare, high and ultra high-speed conditions were generated through AND 123a, OR's 123m and 123n and AND's 121a and 121c which set the high-speed latch 122 and the ultra high-speed latch 124 (FIG. 2t) at decode 5 and decode 8, respectively. Thus, for a few microseconds, carriage advance was called for in low-speed and was then changed to a high-speed and finally an ultra high-speed mode. Of course, no carriage motion actually occurred during this short time. The ultra and high-speed modes are removed a number of lines, for example, at counts of 13 and 11, and 5 and 3, for eight and six lines per inch, respectively, before the stopping point by the reset of the ultra and high-speed latches 124 and 122 through AND's 121d and 121b and OR's 124a and 122a in response to line counts through AND 123g or AND 123h, and OR 123p. Thus, it will be seen that a high-speed skip will occur if the channel skip is to a location 15 or more line spaces away. The specific skip range depends on the carriage drive velocity time characteristic. Likewise, control of the deceleration by decode of the displacement in line increments to the stopping point, using the line counter 150 contents, can be used in other types of carriage mechanisms.

During a space or skip operation, the printer may come to the end of a form 13. When the printer is at the next to last line of a form 13, but the carriage emitter pulse indicating that the form 13 is moving to the last line has not occurred, the CCB address register 56 (FIGS. 2d-e) contains the address of the last line of the form 13 and the CCB register 83 (FIG. 2k) will contain the byte associated with the next to last line of the form 13. When the decode 4 pulse is received for the last line of the form 13, the CCB register 83 will be loaded with a byte containing the flag bit indicating the end of the document 13. Detection of the flag bit resets the CCB address register 56 through AND 175 and OR 174. This is a d-c reset and occurs at RO, overriding the CCB address register 56 advance which normally occurs at RO. When the clock 60 stops at RO, the CCB address is 1, the CCB register 83 contains a flag bit and the form is at the last line and is moving. AND's 57a, 57b

decode address 0 for providing a CCB address 0 or flag at OR 58, and CCB address 1, respectively.

A carriage run away latch 200 (FIG. 2d) is provided which is set through AND 202, reset through OR 201 by carriage go or by an input from OR 172, and provides a run away signal at AND 203 (FIG. 2e) if CCB address 1 occurs with the carriage run away latch 200 set. This senses that two channel 1's occurred during the same forms command so that a complete form has passed by the print line without stopping the mechanism. The parity check circuit 89 (FIG. 2k) is checked for parity every W0 time on an odd bit basis through AND 204. Normally, a carriage emitter signal should occur for every line space although the emitter pulse which occurs during stopping is not functionally necessary. The carriage command register 78 (FIG. 2l) may have been inadvertently loaded with a forms channel digit which was not in fact loaded into the carriage control buffer 40. This is a programming error. When the carriage is set in motion, controls will look for this valid channel in the buffer 40 but none will be found. If a complete form 13 passes by the print line as sensed by the existence of two carriage address 1 conditions in the same command, a channel code did not exist and a carriage run away condition is occurring.

According to the present invention the platen 23 is advanced initially when the printer is set up by the ON output of the timeout latch 222 which is turned on by the not carriage settling signal, which is the inverted output of carriage settling single shot 161a (FIG. 2f), and the print gate latch 254 (FIG. 11) signal through AND 220. This activates single shot 214, through OR 218, energizing the forward operating winding 35 through pick driver 210 to advance platen 23, and turning on latch 216 to energize hold driver 212. Single shot 214 also energizes the latch magnet hold winding 36b by energizing pick driver 244 through inverter 240 and single shot 242, actuating latch armature 36a (FIG. 8) to hold to platen 23 in the advanced or forward position, and setting latch 236 to energize hold driver 238.

Whenever the carriage is advanced by low-speed latch 120 turning on to gate pulses from emitter 111 through one of AND's 110d, 110e, the platen retract magnet winding 36c is energized to actuate latch armature 36a (FIG. 8) free of detent shoulder 23b, from OR 234 and single shot 232 (FIG. 11) through pick driver 228 and hold driver 230. The latch 216 is reset by single shot 232 to deenergize the hold driver 212, and latch 236 is reset to release the armature 36a. This permits springs 33 (FIG. 8) to retract the platen 23 and provide adequate clearance between the platen 23 and the type character levers 11a for the document 13 to advance.

When the carriage stops after advancing the document 13, low-speed latch 120 is turned off, and not low-speed signal energizes the operating winding 35 to advance the platen 23 to the printing position through pick and hold drivers 210 and 212 by turning on single shot 226, which in turn activates single shot 214 through OR 218. Single shot 214 turns on latch 216 to activate the hold driver 212, and through inverter 240 and single shot 242 energizes pick driver 244 and turns on latch 236 to energize hold driver 238 of latch winding 36b.

Thus it may be seen that the invention provides for automatically retracting the platen to provide a maximum of clearance for advancing the document each time the carriage operates, and automatically advances the platen to provide

the optimum operating clearance as soon as the carriage stops so that the best printing conditions are obtained. Troubles caused by interference between the document and type carrier are reduced to a minimum.

5 While the invention has been particularly shown and described with reference to a preferred embodiment thereof, it will be understood by those skilled in the art that various changes in form and details may be made therein without departing from the spirit and scope of the invention.

10 We claim:

1. The combination in a printer having a type carrier and an impact member on opposite sides of a document for performing a printing operation thereon of:

operating means for adjusting the spacing between the type carrier and the impact member,

carriage means for advancing the document between printing operations including a motor having carriage switch means operable to ON and OFF positions to control the advance of the document, and

means for controlling the operating means to increase the spacing between the type carrier and the impact member each time the carriage means advances the document.

2. The invention as defined in claim 1 characterized by the type carrier comprising a plurality of movable character bearing elements moving along a track and provided with actuating means to actuate the elements transversely of the track to impact the document against a platen impact member.

3. The invention as defined in claim 2 characterized by the platen being movably supported for movement toward and away from the type carrier.

4. The invention as defined in claim 3 characterized by the platen member being spring biased away from the type carrier and having electromagnetic operating means to advance it toward the carrier.

5. The invention as defined in claim 4 characterized by the platen member being provided with electromagnetic latch means to latch the platen in an advanced position.

6. The invention as defined in claim 5 characterized by circuit means connected to respond to operation of the carriage switch means to the OFF position and connected to effect operation of the platen electromagnetic operating means.

7. The invention as defined in claim 6 characterized by circuit means connected to respond to operation of the carriage switch means and connected to effect operation of the electromagnetic operating means and the electromagnetic latch means in timed relation.

8. The invention as defined in claim 7 characterized by the electromagnetic latch means having a retract magnet winding for releasing the electromagnetic latch means.

9. The invention as defined in claim 8 characterized by circuit means connecting the retract magnet winding to be energized by the carriage switch means when operated to the ON position.

10. The invention as defined in claim 9 characterized by the electromagnetic operating means and the latch means being provided with bistable switch means and having set and reset operating conditions and carriage switch means being connected to reset said switch means for the electromagnetic operating means and the electromagnetic latch means when it effects energization of the retract magnet winding.
